(74) **Attorney, Agent, or Firm:** Jeenam Park

(57) **CLAIM**

The ornamental design for a shaver, as shown and described.

DESCRIPTION

FIG. 1 is a perspective view of a shaver showing our new design;

FIG. 2 is another perspective view thereof;

FIG. 3 is a front view thereof;

FIG. 4 is a rear view thereof;

FIG. 5 is a right view thereof;

FIG. 6 is a left side view thereof;

FIG. 7 is a bottom view thereof;

FIG. 8 is a top view thereof;

FIG. 9 is an enlarged view of portion "9" shown in FIG. 1;

FIG. 10 is an enlarged view of portion "10" shown in FIG. 2;

FIG. 11 is a perspective view of the shaver, shown with the upper and bottom lids removed, to show aspects of the design not clearly visible when combined;

FIG. 12 is another perspective view of FIG. 11;

FIG. 13 is a right view of FIG. 9;

FIG. 14 is a left view of FIG. 9;

FIG. 15 is a bottom view of FIG. 9;

FIG. 16 is a left view of FIG. 9;

FIG. 17 is an enlarged top view of FIG. 11; and,

FIG. 18 is an enlarged bottom view of FIG. 11.

In the drawings, the evenly spaced broken lines illustrate portions of the article that form no part of the claimed design. The dash-dot broken lines illustrate enlarged view indicators and form no part of the claimed design.

1 Claim, 18 Drawing Sheets
